APPARATUS FOR COATING CORES OR STRANDS

George Weiss, Des Plaines, Ill., assignor to
Standard Cap and Seal Corporation, Chicago,
Ill., a corporation of Virginia

Application November 19, 1931, Serial No. 576,037

5 Claims. (Cl. 91—59.1)

My invention relates to a means and apparatus for coating a core or a strand with a fluxible material and particularly to the apparatus for producing articles covered with a thin and uniform coating of another material.

The invention contemplates the provision of means and apparatus for coating articles with a metallic coating in which the metallic coating is so finely distributed that an even and uniform article is produced.

The invention further embraces an improved apparatus for materially increasing the speed at which the metallic coatings are applied to cores and the inclusion of means for applying a coating which is thin and which is evenly distributed.

The invention also contemplates the provision of means whereby the rate of speed at which the cooling of the metallic coating applied to the core is materially increased without affecting the bond between the core and the coating material, and thus increasing the rate at which the finished article is produced. The apparatus of my invention being of particular service in coating a core or strand preferably fine wire with fluxible material, such as solder, for use in holding the skirts of closure caps upon the necks of milk bottles, though the invention is not to be thus limited.

Wire coated by means of the apparatus of my invention is well adapted for use in a machine for tightly wrapping coated wire about the closure caps of milk bottles and for fluxing the coating of the lapping ends of the applied wire to hold these ends together, an electric current being passed through the wire, causing the lapped ends of coated wire to fuse together to form a band or ring that holds the cap skirts upon the bottle, the coating being sufficiently smooth and free from dross to permit a good fluxing operation and insure circuit terminals having a good contact with the coating.

The apparatus of my invention is inclusive of a receptacle containing a bath of molten fluxible material such as solder and a guiding structure, through which the wire is passed, serving to remove the dross and define the thickness of the coating, also a means of cooling and applying an oil film to the coated wire as it comes out of its molten bath. The oil film on the wire accomplished by means of an idler sheave which is mounted on top of the furnace or heating unit, the sheave being immersed in the oil. As the sheave conducts heat from the wire to the oil, the bath is cooled by means of water cooled coils located in the feeder tank.

The invention will be more fully explained in connection with the accompanying drawings in which Figure 1 is a sectional elevation illustrating the preferred embodiments of my invention;

Figure 2 is a plan view of the structure shown in Figure 1;

Figure 3 is an enlarged sectional side view of the oil bath and oil cooling tanks taken in the direction of arrows 3—3 of Figure 4;

Figure 4 is a plan view of the oil bath and oil cooling tanks shown in Figure 3;

Figure 5 is a plan view of another embodiment of oil cooling tank forming a part of my invention;

Figure 6 is a sectional view taken substantially on a line 6—6 of Figure 5.

The apparatus illustrated includes a receptacle 1 which may be a melting pot for the fluxible material which is to be coated upon the wire that is fed by reel 2 through the molten material. Said receptacle to be passed downwardly through 15 the opening in top of furnace or heating unit 3 through a side of which a gas nozzle 4 is passed, the gas being admitted and ignited to heat receptacle 1 and melt its contents. Two brackets 5 are secured to one side of furnace 3, each bracket 20 having one end of arm 6 in pivotal connection, the two arms being connected at the other end by shaft 7. The two arms 6 are further stiffened by strut 8 and are adjusted to their various positions by post 9, which is screwed into support block 25 10, post 9 being in engagement with one of the arms 6.

The primary guiding is done by sheaves 11, the number of which is dependent upon the number of wires being coated simultaneously. These 30 sheaves are mounted and turn about on shaft 7 and are immersed in the molten material. The wire 12 is supplied from reels 2 and is passed through the molten material by the aforesaid sheaves, which are hollow and are preferably of 35 V-shaped cross section. The guiding structure consists of a member 13 to remove the dross from the wire and the porcelain conduit 14 held in block 15 to keep the dross from the wire as it leaves the molten material. Each wire strand has a 40 conduit 14 whose bore through which it passes is slightly larger than the wire itself. This conduit is located slightly above the level of the molten material and as the dross collects on the surface of the aforesaid material the wire leaves its bath 45 free from all foreign matter. The bore in the porcelain conduit 14 also serves to smooth out and define the thickness of the coating on the wire. The member 15 has a number of U-shaped slots equal to the number of wires being coated 50 which serves to scrape off any dross that might have accumulated on the wire at its entrance into the molten material.

The oil filming tank 17 and oil cooling tank 55 18 are suitably mounted on furnace 3. The wire 12 passes over idler sheave 19 which is covered by a film of oil due to adhesion, and is then wound upon a suitably driven reel (not shown). The oil on the sheave acts as a cooling agent 60

to wire 12 and at the same time creates a protective oil film about the wire. The excess oil on the wires 12 drips off onto tray 20 which slopes downward toward cooling tank 18 and is fastened to plate 21 by means of screws. Tray 20 and plate 21 are fastened to support 22 by means of bolts and nuts and is adjustable to its proper position through slot 23 in plate 21. Tank 18 is separated into two compartments by baffle 24 the lower edge of which is slightly above the bottom of the tank, thus the oil level is kept equal in the two compartments. As the oil dripping from the wires is hot a means for cooling is necessary so a cooling unit or coil 25 is placed in the large compartment in tank 18. This consists of a piece of tubing of copper or any other suitable material wound to take the shape or form of a coil, the ends of which are fastened to the inlet and outlet connections. Water or any other suitable cooling medium is then sent through the coil entering at inlet connection 26 passing upward through the coil and leaving the tank through outlet connection 27. The volume of water passing into the coil may be controlled by a valve such as 29 as the volume of water passing therethrough will greatly affect the temperature. In order to cool and replenish the supply of oil in tank 17 the oil that is carried by the wires is drained by the tray 20 into the small compartment in tank 18 raising the level of the oil which then flows through trough 28 into tank 17, the coil 25 keeping the oil in tank 18 at all times at the proper temperature.

Another embodiment of oil cooling tank has been illustrated in Figures 5 and 6, wherein a tank 30 suitably supports a coil 31 provided with an intake connection 32 having a control valve 45 connected thereto, and an outlet connection 33. I have provided a displacement tank 35 substantially centrally of cooling coil 31 which may be suitably supported or carried by the outlet lead 34 of the coil. As it is desirable to minimize the time required to reduce the temperature of the oil returned to tank 30, the baffles 36 and 37 have been provided, forming compartments 38 and 39, each adapted to receive substantially half of the oil which drains from tray 40. One end of tray 40 has been formed with a lip portion 41 and an extended lip portion 42, so that the oil on tray 40 flows to compartment 38 over lip 41 and to compartment 39 over lip 42. The lower extremity of baffle 37 has been turned inwardly to direct the flow of oil from compartment 38 to one portion of the cooling coil 31, while a plate 43 has been secured to the lower turned extremity of baffle 36, which plate is also connected to the displacement tank 35, and to the tank 30 to direct the oil in compartment 39 to another portion of coil 31. Thus it will be noted that the oil returned to the compartments 38 and 39 is directed to opposite sides of the tank 30 and is cooled by contact with different portions of coil 31. It will also be noted that the space around the coil 31 is small so that the quantity of oil being cooled is confined to the cooling coil and thus a minimum of time is required to cool the oil to a desirable temperature.

It is apparent that, within the scope of the invention modifications and different arrangements may be made other than is herein disclosed, and the present disclosure is illustrative

merely, the invention comprehending all variations thereof.

What I claim is:

1. In a core coating mechanism including means for holding coating material, means for guiding a core through said coating material and means to govern the thickness of the coated core, the combination of a chamber; means having a film of fluid thereon associated with said chamber adapted to envelop said core with fluid; a second chamber having means therein to vary the temperature of fluid; means to supply fluid from said second chamber to said first chamber; and means for regulating the amount of fluid remaining on said coated core and transferring fluid to said second chamber.

2. In a core coating mechanism including means for holding coating material, means for guiding a core through said coating material and means to govern the thickness of the coated core, the combination of a chamber; means having a film of fluid thereon associated with said chamber adapted to envelop said core with fluid; a second chamber having a cooling coil therein to cool fluid; means to supply cooled fluid from said second chamber to said first chamber; and means for regulating the amount of fluid remaining on said coated core and transferring fluid to be cooled to said second chamber.

3. In a machine for coating a core including a support; a receptacle for a coating bath carried by said support; core feeding means; means for guiding a core through said coating bath; means for regulating the thickness of the coated core; a chamber adapted to contain fluid; means for applying a film of fluid to said coated core including a member partially immersed in the fluid in said chamber and adapted to contact with said core; a second chamber having means therein to vary the temperature of the fluid; means to supply fluid from said second chamber to said first chamber; and means for regulating the amount of fluid remaining on said coated core and transferring fluid to said second chamber.

4. In a machine for coating a core including a receptacle for a coating bath; core feeding means; means for guiding a core through said coating bath; means for regulating the thickness of the coated core; a chamber adapted to contain fluid; means for applying a film of fluid to said coated core including a member partially immersed in the fluid in said chamber and adapted to contact with said core; a second chamber having a coil and a displacement member therein to confine fluid adjacent the coil to vary the temperature of the fluid; means to supply fluid from said second chamber to said first chamber; and means for regulating the amount of fluid remaining on said coated core and transferring fluid to said second chamber.

5. In a machine for coating and cooling a core, the combination of means to coat said core; means to cool said coated core by applying a fluid film thereon, including a tank adjacent said coating means and having fluid applying means therein; a second tank associated therewith; means to transfer fluid from said second tank to said first tank; and means to regulate the amount of film on said core and transfer fluid to said second tank.

GEORGE WEISS.
